UNITED STATES PATENT OFFICE.

ALBERT A. WILKINS, OF MIDDLETON, MASSACHUSETTS, ASSIGNOR OF ONE-HALF TO
FREDERICK R. CAMPBELL AND CHARLES E. CAMPBELL, OF LYNN, MASSACHUSETTS.

INCANDESCENT ELECTRIC LAMP.

978,094.

Specification of Letters Patent.

Patented Dec. 6, 1910.

Application filed September 13, 1909. Serial No. 517,358.

To all whom it may concern:

Be it known that I, ALBERT A. WILKINS, a citizen of the United States, residing at Middleton, in the county of Essex and State 5 of Massachusetts, have invented certain new and useful Improvements in Incandescent Electric Lamps; and I do hereby declare the following to be a full, clear, and exact description of the invention, such as will 10 enable others skilled in the art to which it appertains to make and use the same.

The invention relates to incandescent electric lamps.

The object of the present invention is to 15 produce an incandescent lamp having the advantages of the tungsten lamp without its delicacy and at the same time having the strength and durability of the carbon filament lamp.

20 With the above object in view the invention consists in the incandescent lamp hereinafter described and particularly defined in the claims.

The accompanying drawing is a view in 25 elevation of an incandescent lamp embodying the invention.

As shown in the drawing the lamp comprises a bulb 1 of glass provided with an external screw-threaded metal shell 2 and 30 an internal depending stem of glass 4 within which the leading-in wires 6 and 7 are sealed. All of the above elements are of well-known construction in the so-called Edison lamp.

35 The preferred embodiment of the invention comprises a filament composed of alternate sections of carbon and tungsten. The two sections 9 and 10 are of carbon, such as is used in the ordinary carbon filament 40 incandescent lamp, and are attached at their upper ends to the leading-in wires 6 and 7 respectively. The lower ends of the carbon filament sections are cemented to the lower ends of a tungsten filament 12 by means 45 of a suitable cement such as graphite and caramel paste. The tungsten filament is substantially U-shaped and suspended in inverted position from its bend by a hook 14 secured in the glass stem 4.

50 The comparatively stiff carbon filaments act to effectively support the lower ends

of the tungsten filament so that the only other support required is the hook 14 at the bend in this filament. By this construction the glass support for the tungsten filament is entirely eliminated. The carbon supports for the tungsten filament are sufficiently rigid and at the same time sufficiently elastic to allow the lamp to be supported horizontally or at any desired degree 60 of inclination. The lamp thus has the efficient light giving properties of the tungsten lamp with the durability and strength of the carbon lamp.

It is to be observed that various combinations of carbon and tungsten filaments may be made both as regards size and length of the portions, thus by increasing the length of the carbon filament and decreasing the length of the tungsten filament a comparatively cheap, low candle power, efficient lamp is produced. The carbon and the tungsten are bodies of different specific resistances and the invention contemplates in its broader aspects the use of a light giving 75 element composed of sections of substances of different specific resistances. It is also to be observed that the co-efficients of resistance of the two substances are the one positive and the other negative, and this is 80 of value for reasons apparent to those skilled in the art.

The invention lends itself to the production of lamps of widely varying candle power, all of which have a resistance suitable 85 for use on ordinary incandescent circuits.

Having thus described the invention, what is claimed is:

1. An incandescent electric lamp the light 90 giving element of which is composed of alternate sections having positive and negative co-efficients of resistance, substantially as described.

2. An incandescent electric lamp the light 95 giving element of which is composed of sections of carbon and tungsten arranged in series, substantially as described.

ALBERT A. WILKINS.
